CLAIM

The ornamental design for a keypad for door lock, as shown and described.

DESCRIPTION

FIG. 1 is a top, front, right side perspective view of a first embodiment of a keypad for door lock;

FIG. 2 is a front elevation view of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1;

FIG. 7 is a bottom plan view of FIG. 1; and,

FIG. 8 is a cross sectional view taken along line **8-8** of FIG. 2.

The dash-dash broken lines show portions of the keypad for a door lock that form no part of the claimed design. The dot-dash broken lines represent boundaries of the claimed design and form no part of the claimed design. The dash-dash broken lines radiating from the bar shown in FIGS. 1, 2, 4, 5, 6 and 8 represent illumination only and form no part of the claimed design.
